UNITED STATES PATENT OFFICE.

CHARLES H. SWARNER, OF OMAHA, NEBRASKA.

BUNDLE-WAGON FOR THRESHERS.

1,135,073.

Specification of Letters Patent. Patented Apr. 13, 1915.

Application filed March 2, 1914. Serial No. 822,085.

To all whom it may concern:

Be it known that I, CHARLES H. SWARNER, a citizen of the United States, residing in the city of Omaha, county of Douglas, and State 5 of Nebraska, have invented certain new and useful Improvements in Bundle-Wagons for Threshers, and have described the same in the following specification, illustrated by the accompanying drawings.

10 My invention relates to vehicles or wagons of that class which are commonly used in the harvest field as tenders to supply bundles, or sheaves, of small grains to thrashing machines.

15 It is the main object of the invention to lessen the cost of harvesting the grain by diminishing the cost and the labor of delivering the sheaves to the thresher; to lighten the necessary labor of the helpers employed

20 for the purpose of unloading the bundles from a vehicle of this kind and to diminish the necessary number of such helpers, by the use of power for that purpose; to prevent the loss of scattered grain, separated from

25 the straw in the wagon, by delivering all such separated grain to the thresher without waste; and in general to increase the efficiency of wagons of the specified class. To accomplish these results I incorporate in my

30 improved wagon an endless conveyer running in the bottom thereof, and an elevator meeting the conveyer, and provide transmission gearing for driving the conveyer and the elevator from the power shaft of the

35 associated thresher.

In the accompanying drawings, illustrating the best manner in which I have contemplated applying the principles of my invention, Figure 1 is a plan of a bundle wagon 40 which is constructed and associated with a threshing machine, in accordance with these principles. Fig. 2 is a side elevation of the same. Fig. 3 is a longitudinal vertical section of the principal parts of the wagon on 45 the section line 3—3 of Fig. 1. Fig. 4 is an enlarged detail, supplementing Fig. 3, on the same section line. Fig. 5 is a rear end elevation of the same wagon, showing the elevator in vertical position, as shipped for 50 locomotion.

In this illustrative and illustrated specimen of my invention, the wagon floor 1, carried by the frame 1' on the bearing wheels 2, is divided through the middle from end to 55 end by a longitudinal opening into the sub-

jacent trough 3, which is of uniform rectangular cross section, and marginally flush at the top with the top surface of the floor. In this trough and below the level of the floor, runs the horizontal endless conveyer 4, 60 which is supported by the shelf 5 to prevent sagging, and is provided with the transverse slats 6 to prevent its load from slipping. On this floor is supported the false floor 7, separated therefrom by a plurality 65 of thin chambers 44 in which the metallic plates or covers 8, having handles 9, are independently slideable transversely by hand to open and close the trough wholly or partly as occasion may require. The sides 10 and 70 the connecting ends 11 of the wagon body, or box, are held removably to the frame 1' by a plurality of vertical posts 12, inserted in slots formed by the keepers 13. On the transverse shaft 14, which is journaled at 75 the rear end of the frame 1', are keyed the driving roller 15 of the conveyer 4, a pair of sprocket wheels 16, and the bevel gear 17; while on the swinging horizontal countershaft 18, which is suspended from the shaft 80 14 by the loose hangers 19, are keyed the sprocket wheels 20, connected with the sprocket wheels 16 by the sprocket chains 21. On this countershaft, and in terminal pivotal contact with this transverse shaft, is 85 pivoted the trough-shaped elevator frame 22; while lengthwise in the trough, and actuated by the roller 23 on the gear shaft 18, runs the endless carrier 24, having the transverse slats 25 and the teeth 26 for engagement with the bundles of grain. To raise and lower the elevator, it is attached by the ropes 27 to the drums 28, which are keyed to the transverse shaft 29, the latter being journaled to the rear end of the wagon body 95 90 and provided with the hand-crank 30, the ratchet wheel 31 and the pawl 33.

For the purpose of driving the elevator and the conveyer, power is communicated to the shaft 14 by the bevel gear 17 thereon, 100 which meshes with the similar gear 35 on the horizontal shaft 36. This shaft 36, being square in cross section, is provided with a sleeve 37, slidably adjustable thereon. By this sleeve the shaft 36 is coaxially and operatively connected, from time to time, with the similar horizontal shaft 38, which is journaled in the extension 39 of the frame of the associated thresher 40, and is driven 105 from the thresher engine by the pulleys 42 110

and the belts 41. By means of a clutch not shown, which is operated by the hand lever 43, this horizontal shaft is stopped, and the conveyer and elevator are thereby rendered 5 inoperative, whenever desired, during the operation of the thresher.

In use the wagon, with the elevator adjusted as in Fig. 5, and with the conveyer trough closed by the covers, is drawn from 10 place to place in the harvest field, collecting the bundles in the usual way. When loaded, the vehicle is drawn to the thresher, the coaxial shafts 36 and 38 are united by the sleeve 37, and the elevator is tilted by manipulation 15 of the crank to an oblique position, so as to overhang the feeder of the thresher, as indicated in Fig. 2. Then, the thresher engine being started, and the conveyer and elevator being in action, one of 20 the covers 8 is drawn aside from the conveyer trough, as in Fig. 1, and then the others successively at intervals, whereby the sheaves are permitted to work down slowly, a few at a time, either automatically or by 25 the aid of one or two helpers in the wagon, into the trough and onto the conveyer, whereby they are transferred to the elevator, and by the elevator to the thresher.

The wagons are preferably made of large 30 capacity, and the saving of labor which they accomplish is very great. Also the ground space between the wagon and the thresher, permits the separator man to pass freely between them for all necessary purposes; 35 and the unloading of the wagon is accomplished without exposing the bundles, while being transferred to the thresher, to the effects of those high winds which frequently prevail during harvest in some parts of the 40 country.

I claim as my invention—

1. A vehicle of the specified class, comprising a transverse shaft, journaled in bearings at the rear end of the vehicle, an 45 endless conveyer running in a longitudinally

disposed trough under the floor of the vehicle, and having its driving roller keyed on said shaft, a pair of sprocket wheels and a bevel gear wheel which are keyed on said shaft, a pair of pivoted hangers dependent 50 from said shaft, a swinging countershaft journaled in the hangers, a pair of sprocket wheels keyed on the countershaft, sprocket chains connecting said pairs of sprocket wheels, an elevator frame terminally pivoted 55 on the countershaft, means for raising and lowering the free end of the elevator frame, an endless carrier working in the elevator frame and having its actuating roller keyed on the countershaft, a bevel gear meshing 60 with the first-mentioned bevel gear, and a sleeve on the pinion of said meshing gear for engaging an alining shaft of a threshing machine.

2. A vehicle of the specified class, comprising a shaft journaled in bearings at one end of the vehicle, an endless conveyer running in the bottom of the vehicle, and having one of its rollers keyed on said shaft, a pair of sprocket wheels and a bevel gear 70 which are keyed on said shaft, a pair of dependent hangers pivoted on said shaft, a swinging countershaft journaled in the hangers, a pair of sprocket wheels keyed on the countershaft, chains connecting the pairs 75 of sprocket wheels, an elevator frame pivoted on the countershaft, an endless carrier working in the frame and having its actuating roller keyed on the countershaft, a bevel gear meshing with the first-mentioned bevel 80 gear, and means for connecting the pinion of said meshing gear with a power shaft in alinement therewith.

In testimony whereof I subscribed this specification in the presence of two wit- 85 nesses.

CHARLES H. SWARNER.
